(57) **CLAIM**

The ornamental design for a multi-purpose hand operated office utensil, as shown and described.

DESCRIPTION

FIG. 1 is a first perspective view of a multi purpose hand operated office utensil showing my new design;
 FIG. 2 is a second perspective view of FIG. 1;
 FIG. 3 is a third perspective view of FIG. 1;
 FIG. 4 is a fourth perspective view of FIG. 1;
 FIG. 5 is a front elevational view of FIG. 1;
 FIG. 6 is a rear elevational view of FIG. 1;
 FIG. 7 is a rightside elevational view of FIG. 1;
 FIG. 8 is a leftside elevational view of FIG. 1;
 FIG. 9 is a top plan view of FIG. 1; and,
 FIG. 10 is a bottom plan view of FIG. 1.

The features shown in dotted lines form no part of the claimed design.
